CATHODE SUPPORT FOR ELECTROLYTIC UNITS

Kenneth C. D. Hickman, Rochester, N. Y., assignor by mesne assignments, to Eastman Kodak Company, Jersey City, N. J., a corporation of New Jersey

Application December 17, 1935, Serial No. 54,874

4 Claims.

(CL. 204—5)

The present invention relates to improvements in cathode supports for electrolytic units, and more particularly to means for supporting the cathodes within an electrolytic unit for recovering silver from a used photographic fixing bath.

In many of the electrochemical reactions for depositing metal upon cathode plates, and particularly in the electrolytic deposition of silver from silver laden fixing baths, priming nuclei are continually deposited, and the metal deposit spreads from any point where the cathodes touch the wall of the container. In time, this metallic deposit reaches the anode and the cell becomes short circuited.

15 The primary object of the present invention is to provide a supporting arrangement for the cathode plates, such that the natural tendency of a conducting deposit to spread between the cathode and anode is considerably reduced or entirely eliminated.

Another object of the invention is the provision of supports for the cathodes in an electrolytic unit such that a longer path is provided for the spontaneous growth of the metal deposit 25 from the cathode.

A further object of the invention is the provision of cathode supports which induce preferential deposition of the metal away from the contact edge of the cathode.

30 Still another object of the invention is the reduction to a minimum of the boundary on the cathode where the adverse conditions exist.

A still further object of the invention is the provision in an electrolytic unit, provided with 35 an electrolyte agitating means, of a connection between the cell and the cathode, and including a flexible portion so that the aforementioned spontaneous deposits of metal or silver may be broken up or cleared away by the circulation of 40 the electrolyte.

Other and further objects of the invention will be suggested to those skilled in the art by the description which follows.

45 The above and other objects of the invention are obtained in an electrolytic unit which comprises a cell for containing the electrolyte, a cathode for immersion in the electrolyte and adapted to receive a plating current, a connection for locating the cathode with respect to the cell, and a member within said connection and having a formation for minimizing the deposit of metal 50 in the vicinity of said connection, and providing a tortuous path for the spontaneous metallic deposit which tends to extend from the cathode and along

the surface of the connection and cell to the anode.

Reference is hereby made to the accompanying drawing wherein like reference characters designate similar elements, and wherein:

5 Fig. 1 is a vertical cross-section of an electrolytic unit in which the cathodes are supported according to the invention.

Fig. 2 is a perspective view of a cathode support and a member for minimizing the deposit of metal 10 on said support.

Fig. 3 is also a vertical cross-section of an electrolytic unit with two different types of cathode supports.

Fig. 4 is a section taken on the line 4—4 of 15 Fig. 3.

The present invention is applicable to many types of electrolytic units, but for the purposes of illustration is disclosed as applied to a unit which comprises a cell 10 having side walls 11 and a bottom wall 12. A rotating shaft 13 extends longitudinally of the cell 10 and carries a plurality of arms 14. The side walls 11 of cell 10 may be provided with grooves 15. The cell 10 is adapted to contain an electrolyte 16 which may fill the cell 10 20 to any predetermined level. The electrolyte is selected according to the character of the electrochemical reaction to be performed within the electrolytic unit, and is preferably silver laden photographic fixing solution.

30 A cathode 17 is immersed in the electrolyte and is connected to a source of electrical energy so that a plating current flows from the anode (not shown) through the electrolyte 16 and to the cathode 17. This flow of plating current causes 35 deposition of metal upon the cathode 17 in a known manner.

The preferred form of cathode and cathode supporting arrangement is disclosed in Figs. 1 and 40 2. The side edges of cathode 17 fit into the grooves 15 in the side walls of the cell 10. Said side edges of the cathode 17 are cut away as at 18 so as to be spaced from the side walls 11 and the grooves 15 therein. Recesses 19 are provided in 45 the side edges of cathode 17.

A plurality of connections are provided between the cathode 17 and the side and bottom walls of the cell 10. These connections may assume any of several forms and are preferably provided as 50 feet 20 which are connected to cathode 17 within the recesses 19 thereof. The connection for supporting the cathode within the cell may also be composed of feet 21 connected to the lower edge of cathode 17 and adapted to extend into grooves 22 55

which are provided along the edges of supporting blocks 23 on the bottom wall 12 of the cell 10.

Under actual plating conditions there is a natural tendency for the spontaneous deposit of metal to extend from the cathode 17 along the feet members 20 and 21 and along the walls of the cell 10 to the anode. As before mentioned, such deposit of metal will in time short-circuit the cell.

10 According to the invention a member is interposed or inserted into the connection between the cathode and the cell and functions to minimize the deposit of metal in the vicinity of said connection. A bell-shaped or skirted member 24 will reduce the spontaneous growth of the metallic deposit to a minimum. Such member 24 has a dome portion 25 which covers the end of the feet 20 or 21 within the grooves 15 or 22 of the side walls 11 or supporting blocks 23. Member 20 24 also includes a skirt portion 26 which flares out from said dome portion 25, and which surrounds or encircles those portions of the feet members 20 and 21 which extend to the edges of cathode 17. The member 24 may be composed of 25 rigid insulating material, such as glass, Celluloid, hard rubber, Bakelite, etc.

The tortuous or devious path for the plating current leak along the cell and connection to the cathode reduces the spontaneous growth of metal 30 along that path, and in turn reduces the possibility of a short-circuit within the cell. The member 24 may also be composed of a flexible insulating material, such as rubber. This composition of the member 24 is particularly useful 35 within cells which require an agitating member because circulation of the electrolyte will then cause flexing of the skirt portion 26 of the member 24 and breaking up of the metallic deposit which is formed along the surface of said member 24. In this way the protective member for the cathode connection will be self-cleansing.

It is pointed out that the arrangement for supporting the cathode 17 as disclosed in Figs. 1 and 2 by virtue of the skirt portion 26 of the member 24 reduces or eliminates the undesirable growth of metal from the cathode, either by providing a longer journey for the deposit from the cathode to the anode, or by providing a longer path for the electric plating current in the region 40 where the undesirable deposit may start, or by inducing preferential deposition away from the contact edge of cathode 17. The undesirable deposit is also reduced or eliminated by providing the feet members 20 and 21 so that the area where 45 the adverse conditions exist is reduced to a minimum. Finally, any deposit that may occur is automatically cleared away by reason of the fact that the skirt portion 26 may be flexible and may be moved by circulation of the electrolyte to break 50 up any deposit that has been formed along the member 24.

Other arrangements for supporting the cathode plate in such an electrolytic unit are disclosed in connection with Figs. 3 and 4. In this case the 60 cathode 27 fits into the grooves 15 of the side walls 11 along the entire length of said cathode 27. A strip 28 of insulating material is inserted between the side edges of cathode 27 and said grooves 15. Said strip 28 extends along each 65 side of the edge of cathode 27, and reduces or eliminates the spontaneous deposit of metal from the cathode edge along the walls of cell 10 in the same manner as did the skirted member 24 of the previous form of the invention. The strip 28 may 70 also be of flexible material so that this inter-

vening member will also be self-cleansing upon being flexed by the circulation of the electrolyte.

Similar but shorter flexible strips 29 are inserted between the lower edges of the cathode 27 and the grooves 22 within the supporting blocks 23. 5 As before, these strips 29 are of insulating material and provide a tortuous or devious path for the spontaneous growth of metal from the cathode, or for the plating current leak along the walls of the cell to the cathode. Also, these strips 10 29 may be flexible so as to be movable by circulation of the electrolyte to prevent the deposit of metal therealong or to break up any deposit that may have formed thereon.

Another advantage of the interposed members 15 24 according to the invention is produced by use of these members in connection with an electrolytic unit in which the electrolyte is circulated. In many electrochemical reactions, and particularly in a deposit of silver from used photographic 20 fixing baths which are vigorously stirred, the rate of deposition is promoted or increased by continually removing the electrolyte, from which the metal has been deposited, away from the cathode. Conversely, there is very little, if any, metal deposited from a stagnate pool or portions of the electrolyte which are near the cathode. The skirted member 24 protects the electrolyte in the vicinity of feet members 20 and 21 from being circulated by the agitating means consisting of 30 shaft 13 and arms 14. Similarly, the strips 28 and 29 along the edges of cathode 27 provide stagnate bodies of electrolyte along the edges of the cathode, and in this way further reduce the spontaneous deposit of metal along those portions of 35 the cathode. In practical operation these methods of supporting the cathodes have proved indispensable and contribute in a large part to the solution of a difficult problem—that of removing metallic silver from a used photographic fixing 40 bath.

Other forms of supports may be designed to include or incorporate the features and advantages of the supports disclosed herein. However, the invention is not to be limited by the illustrated 45 modifications but only by the scope of the appended claims.

Having now particularly described my invention what I desire to secure by Letters Patent of the United States and what I claim is:

1. An electrolytic unit for depositing a metal from an electrolyte, comprising a cell adapted to contain the electrolyte to a predetermined level and having side walls which are provided with grooves, a cathode adapted to be immersed in 55 said electrolyte and having side edges which are cut away below the level of the electrolyte and which submerged side edges are provided with a recess, a connection attached to said cathode within the recess thereof and for engaging the 60 side walls of the cell to position the cathode therein, and a skirt member encircling said connection within said recess and for minimizing the deposition of the metal on said connection.

2. An electro-plating unit for depositing metallic silver from a used photographic fixing bath, comprising a cell adapted to contain to a predetermined level said used fixing bath as an electrolyte and having walls which are provided with grooves, a cathode adapted to be immersed in 70 said electrolyte and having edges which engage said grooves above the level of the fixing bath electrolyte and which are cut away below the level of the electrolyte to be spaced from said side walls, the submerged side edges of said cath- 75

ode being further provided with a recess, an agitating means for circulating electrolyte across said cathode, a foot member attached to said cathode within the recess thereof and for entering the grooves in said cell to position the cathode therein, and a bell-shaped sheath member having a dome portion between said foot member and the engaged groove and having a skirt portion extending into the recess of said cathode and encircling said foot member in spaced relation thereto.

3. An electro-plating unit for depositing metallic silver from a used photographic fixing bath, comprising a cell adapted to contain to a predetermined level said used fixing bath as an electrolyte and having walls which are provided with grooves, a cathode adapted to be immersed in said electrolyte and having edges which engage said grooves above the level of the fixing bath electrolyte and which are cut away below the level of the electrolyte to be spaced from said side walls, the submerged side edges of said cathode being further provided with a recess, an agitating means for circulating electrolyte across said cathode, a foot member attached to said cathode within the recess thereof and for entering the grooves in said cell to position the cathode therein, and a bell-shaped sheath member having a dome portion between said foot member and the engaged

grooves and having a skirt portion extending into the recess of said cathode and providing a devious path for the spontaneous metallic deposit from the edges of said cathode.

4. An electro-plating unit for depositing metallic silver from a used photographic fixing bath, comprising a cell adapted to contain to a predetermined level said used fixing bath as an electrolyte and having walls which are provided with grooves, a cathode adapted to be immersed in said electrolyte and having edges which engage said grooves above the level of the fixing bath electrolyte and which are cut away below the level of the electrolyte to be spaced from said side walls, the submerged side edges of said cathode being further provided with a recess, an agitating means for circulating electrolyte across said cathode, a foot member attached to said cathode within the recess thereof and for entering the grooves in said cell to position the cathode therein, and a bell-shaped sheath member having a dome portion between said foot member and the engaging grooves and having a flexible skirt portion surrounding said foot member to provide a stagnant body of electrolyte in the vicinity of said foot member and movable by the circulation of said electrolyte to dislodge any deposit of metal that may form on said skirt portion.

KENNETH C. D. HICKMAN.
